UNITED STATES PATENT OFFICE

FRITZ THIERY, OF BERLIN-SIEMENSSTADT, AND HERMANN GOETSCH, OF BERLIN-CHARLOTTENBURG, GERMANY, ASSIGNORS TO SIEMENS & HALSKE AKTIENGESELLSCHAFT, WERNERWERK, OF SIEMENSSTADT, NEAR BERLIN, GERMANY

CARTRIDGE FUSE

Application filed September 16, 1927, Serial No. 220,025, and in Germany November 9, 1926.

The object of the present invention is a cartridge fuse with one or with a plurality of heat coils which are soldered with an easily melted solder. The invention is particularly adapted for the protection of apparatus operating with low tension, such as the equipment used in telephone and other communicating systems.

In the drawing annexed—

10 Fig. 1 is a view of a sectional view of a fuse;

Fig. 2 is an enlarged view of the heat coils 1 and 2 of Fig. 1;

15 Fig. 3 is another form of heat coil embodying the invention;

Fig. 4 is a view showing a method of soldering shorter turns of constantan wire.

According to the invention, the dimensions of the resistance wire of the heat coils are such that the least possible resistance corresponds to a high relative value of the melting current in ampere and static load capacity in joules. To explain this a little more in detail, it may be pointed out that a distinction must be drawn between steady loading of a fuse, as for instance by continuous current flow, and momentary loading due to transient currents which may be caused by atmospheric discharges or by changes in current in adjacent high tension lines. The effect of these momentary currents can be easily reproduced in the laboratory by the discharge current of a condenser. Tests have therefore been made by using a condenser 35 which was charged up to a specific voltage and then discharged through the fuse. The energy of a charged condenser is represented by

$\frac{CV^2}{2}$ and is measured in joules. It was found

40 in practice that fuses which resist the discharge of a condenser the electrostatic energy of which is ascertained to be 12 joules, will withstand almost all atmospheric discharges or discharges of power lines which are likely 45 to occur.

It is desirable that atmospheric discharges, such as take place during stormy weather, shall not blow the fuses, since the equipment is sufficiently protected by the lightning ar- 50 rester. Hence, the object of the invention

is to design a fuse which while blowing with a comparatively small steady current, will be able to resist a considerable momentary surge, and the value of 12 joules given was found to be a suitable one.

55 Fuses according to the invention, can easily be so constructed that their melting current is about 0.5 amperes, steady load, with a static load capacity of about 12 joules and a resistance of about 2 ohms.

60 It will be apparent that such fuses are of great importance for protecting feeble current apparatus against excess currents due to any cause, particularly those due to the influence of adjacent power lines. The melting current of known fuses is usually so high (about 8 amperes), that the excess tension fuses or small lightning arresters are generally already damaged before the fuses operate. If, however, the tension fuses are placed 65 in series with fuses of low steady melting current and high static load capacity, it is a simple matter to cause their operation at the proper moment and before the blowing of the tension fuse or lightning arrester to 70 cut off the current without damaging the equipment.

75 The physical structure of cartridge fuses is well known and shall not be discussed in detail in this specification. However, it may be mentioned briefly, that the structure best suited for use with the present invention comprises a glass cartridge closed at both ends with metal members which are adapted to be inserted in the usual fuse holder. Inside of 80 the cartridge may be placed one or more heat coils united by solder.

85 The invention is illustrated in the accompanying single sheet of drawing, showing two forms of carrying out the invention.

90 In one form of carrying out the invention, shown in Figs. 1 and 2, the fuse insertion comprises two heat coils 1 and 2 having resistances made of chromic nickel or constantan, and soldered together at point 3 by means of easily flowing solder, preferably such as Wood's metal. The resistance loop is illustrated on a larger scale in Fig. 2, the reference numeral 3 denoting the solder point, and the numerals 4 and 5 indicating the point where the resist-

ance loops 1 and 2 are attached to the springs 6 and 7. These springs in turn are attached to the fuse members 8 and 9 holding the glass cartridge 10. Arcing is in this case to a certain extent prevented by the resilience of the springs which draw apart quickly when the fuse blows. The prevention of arcing can be further improved, however, and the ohmic resistance can be reduced, if chromic nickel wire 10 is employed, by soldering the heat coils to copper turns. The ohmic resistance drops in this case to 0.1-0.2 ohms.

Similar relationships occur when the fuses are made of spirally wound constantan wires. 15 The static load capacity is somewhat higher in that case (about 14 joules), but the ohmic resistance is also higher. Referring to Figs. 3 and 4, this resistance can be considerably reduced (to about 1 ohm) by soldering or 20 welding only a few turns, preferably only 2 turns of constantan wire 11 on each side which are joined by Wood's metal at point 12, to a spiral spring 13 made of bronze wire. The spiral spring is attached to the metal members of the cartridge. 25

In order to avoid losses in all the above mentioned forms of carrying out the invention, it is important to place the fuse insertion in glass cartridges, and to select these so as to 30 correspond to the static load.

What is claimed is:

1. A fuse comprising two single turns of nickel alloy wire soldered together by means of low-melting-point solder, having a resistance of not more than 0.2 ohms and a static load capacity of 12 joules. 35

2. A cartridge fuse of low melting point with steady load and a high static load capacity comprising loops of chromic nickel wire soldered together with low-melting-point solder, having a resistance of not more than .2 ohms. 40

In witness whereof, I hereunto subscribe my name this 2nd day of August, A. D. 1927.

FRITZ THIERY.

45 In witness whereof, I hereunto subscribe my name this 2nd day of August, A. D. 1927.

HERMANN GOETSCH.
